UNITED STATES PATENT OFFICE.

HERMAN H. LEONARD, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS.

DRIVE FOR SPINNING FRAMES OR SIMILAR MACHINES.

Application filed December 29, 1927. Serial No. 243,343.

This invention relates to the driving mechanism for a spinning frame or similar machine where the spindles or similar elements occur in large numbers and are driven by 5 belts from a common driving drum.

In such machines, it is of great importance that all the spindles or similar elements shall, so far as possible, be driven at the same speed and that the frictional resistance 10 between the driving belt and each spindle shall be the same.

The object of the present invention is to secure this result by driving large groups 15 of the spindles or similar elements, each group by a single belt having substantially the same degree of frictional engagement with each.

The object of the invention is further to provide a simple and efficient means common 20 to two adjacent groups for taking up slack in the two belts and for placing the same tension on both belts.

The nature and objects of the invention will appear more fully from the accompanying 25 description and drawings and will be particularly pointed out in the claims.

The invention in its preferred form is shown as arranged for the driving of a series 30 of spindles through their whirls in a ring spinning frame and as the invention only has to do with the drive and as this type of machine is otherwise well known and familiar to those skilled in the art, it is only necessary here to illustrate and describe those 35 portions of a ring spinning frame with which the present invention is directly concerned.

In the drawings:

Fig. 1 is a top plan view, somewhat diagrammatic, of a longitudinal section of a 40 portion of a ring spinning frame.

Fig. 2 is a detail, partially in vertical cross section, showing the driving belt passing around the whirl of a single spindle.

The elements to be driven are here shown 45 as vertical spindles provided with vertical whirls such as employed in a ring spinning frame. These spindles are indicated diagrammatically arranged in long, equally spaced rows, one row at each side of the

frame, as is usual. The spindles are arranged in groups of eight spindles, four at each side of the frame and all driven by a single belt. Thus in the first group shown, there are the spindles 1, 2, 3 and 4 at the 55 left, viewing Fig. 1, and 5, 6, 7 and 8 at the right. These spindles are supported as usual upon the girders or rails 9 and 10 at the sides of the frame.

Each spindle or similar element may be 60 constructed as desired, but is shown in Fig. 2 as arranged for ring spinning. Here the spindle, such as 4, is mounted in a bearing 11 secured to the girder 9 and carries the whirl 12 around which passes the belt 13. 65

All the eight spindles of the group are driven by the single belt 13 from the driving drum 14 extending the length of the frame. It is desirable that there shall be substantially the same length of peripheral 70 contact of each whirl with the belt and a contact of not less than substantially ninety degrees of the periphery and this is secured by the present invention by the arrangement illustrated. An idler roll 15 is located between the two rows of whirls and preferably 75 between the drum 14 and one row of whirls, such as the row 5, 6, 7 and 8, and midway between the middle two whirls, such as 6 and 7, of that row. The endless belt 13 passes around the entire group of eight whirls and between the whirls 6 and 7 passes 80 around the idler 15. This belt also passes twice only around the drum 14 and only in the same direction, once between the first 85 and second whirls, as 1 and 2 of the group at the left, and once between the second and third whirls, such as 2 and 3 of the same row. That is to say, assuming that the drum is 90 rotating in the direction of the arrow 16, the belt will be traveling in the direction of the arrows shown adjacent the belt. Consequently the portion of the belt shown as running from between the whirls 1 and 2 around the drum and the portions of the 95 belt shown as running from between the whirls 2 and 3 around the drum both travel in the same direction.

With this arrangement the desired result is secured and all the whirls of the group 100

will be driven by the single belt under the same conditions.

Preferably, as shown, the endless belt 13 is flat and therefore its flat side must engage 5 each whirl and also the periphery of the drum each time it passes around the drum. But as the whirls are vertical and the drum is horizontal, deflecting idler rolls 17 and 18 are shown arranged to rotate on a horizontal 10 stud 19 supported on a bracket 20 from the girder 9 adjacent the first row of spindles. The idler roll 17 is located adjacent the second whirl, as 2, engaging the run of the belt from that whirl to the drum and the 15 idler roll 18 is similarly located adjacent the third whirl, as 3, so that the run of the belt in each case which passes from a whirl to the drum is deflected so that its flat surface passes on to the drum concentric to the drum.

20 It is necessary to provide means for taking up the slack in the belt and for producing the required tension on the belt. As it is desirable that all the spindles or similar elements shall be run at the same speed 25 and with the same frictional resistance, this invention provides uniformity of these conditions over a large number of spindles. This result is secured by a slack take-up and tension producing means common to two 30 adjacent groups, such as just described.

An adjacent group of spindles is shown, viewing Fig. 1, below the group just described and the arrangement of this second group with respect to all the elements is 35 the same as that described excepting that the entire system is reversely disposed with respect to the drum. This is indicated by the numbering of the spindles or whirls 1, 2, 3 and 4, and 5, 6, 7 and 8 with the idler 40 roll 15.

The idler rolls 15 are both carried by bell crank levers fulcrumed at 21 on brackets 22 supported from the respective girders. The longer arms 23 of these bell cranks carry 45 journaled at their ends the respective idlers 15, while the shorter arms 24 are connected by a common contractile connector, herein shown as a rod 25 having a turnbuckle 26 by which its length may be adjusted and 50 a contractile spring 27, the spring and rod being arranged in tandem. It will thus be seen that the spring 27 acts equally on the two bell cranks and causes each idler automatically to take up the slack in its 55 belt and also automatically places the same tension on both belts and that the degree of tension thus placed on both belts is adjustable by means of the turnbuckle 26. Thus the two groups of sixteen spindles in 60 all are driven by the two belts at the same speed and under the same conditions and with the same tension on the driving belts, so that all sixteen spindles are driven under uniform conditions.

Having thus described the invention, what 65 is claimed as new, and desired to be secured by Letters Patent, is:

1. In a spinning frame or similar machine, the combination of a horizontal driving drum, four spindles having vertical 70 whirls arranged in a row at each side of the drum, an idler located between the two rows of whirls and midway the middle two whirls of one row, and an endless belt passing around the entire group of eight whirls, 75 around the idler, and twice only around the drum and only in the same direction, once between the first and second whirls and once between the second and third whirls of the other row.

2. In a spinning frame or similar machine, the combination of a horizontal driving drum, four spindles having vertical 80 whirls arranged in a row at each side of the drum, an idler located between the two rows of whirls and midway the middle two whirls of one row, an endless flat belt passing around the entire group of eight whirls, 85 around the idler, and twice only around the drum and only in the same direction, once 90 between the first and second whirls and once between the second and third whirls of the other row, and deflecting idler rolls located adjacent the said second and third whirls and engaging the runs of the belt 95 from the said whirls to the drum.

3. In a spinning frame or similar machine, the combination of a horizontal driving drum, four spindles having vertical 100 whirls arranged in a row at each side of the drum, an idler located between the two rows of whirls and midway the middle two whirls of one row, an endless flat belt passing around the entire group of eight whirls, 105 around the idler, and twice only around the drum and only in the same direction, once between the first and second whirls and once 110 between the second and third whirls of the other row, and deflecting rolls engaging the runs of the belt from the whirls to the drum to insure the belt in each case passing on to the drum with its flat surface concentric therewith.

4. In a spinning frame or similar machine the combination of a horizontal driving drum, two adjacent groups of eight spindles, whirls, idler and endless belt each arranged and cooperating with the drum as defined in claim 1, the elements of one group being reversely disposed with respect to the drum from the elements of the other group, in which the two idlers are mounted for bodily movement and in which a contractile connector extends between the two idlers, causing each idler automatically to take up slack in its belt and placing the same tension on both belts.

5. In a spinning frame or similar ma-

chine, the combination of a horizontal driving drum, two adjacent groups comprising a plurality of whirls, a bodily movable idler and an endless belt passing around all the 5 said whirls, idler and drum, and a contractile connector extending between the idlers of the two groups acting to cause each

idler to take up slack in the belt of its group and acting to place the same tension on both belts. 10

In testimony whereof, I have signed my name to this specification.

HERMAN H. LEONARD.
